UNITED STATES PATENT OFFICE.

ROY W. BROWN, OF AKRON, OHIO, ASSIGNOR TO THE FIRESTONE TIRE AND RUBBER COMPANY, OF AKRON, OHIO, A CORPORATION OF OHIO.

HEAT OR VULCANIZING DEVICE.

Application filed February 9, 1925. Serial No. 7,736.

This invention relates to heating and vulcanizing devices and particularly to horizontal or other heaters for curing articles under the pressure of the vulcanizing medium only.

5 The present invention is particularly adapted to heaters or vulcanizers for vulcanizing boots and shoes.

Heretofore it has been proposed to vulcanize articles of the class described in heaters through which the curing medium, such as air or other gases, is circulated at atmospheric or higher pressures. Various devices for this purpose have been used, one type of device being a vulcanizer formed as a jacketed cylinder through the jacket of which a heating medium, such as steam, has been circulated to warm the air or other gases circulated through the vulcanizer.

One object of the present invention is to 20 provide an improved vulcanizer, some of the features of which may be applied to the above type of vulcanizer whereby better results are secured, but which preferably is adapted to a structure in which the heating 25 medium is passed through a separate heater in a circuit with the vulcanizer.

Another object of the invention is to provide means in a vulcanizer adapted to thoroughly and uniformly mix the heating 30 medium.

Another object of the invention is to provide means adapted to protect rubber or other articles to be heat treated from the local action of a heating medium, such as 35 steam, in a jacketed vulcanizer or from the local cooling action on articles supported in non-jacketed heaters near the walls of the heaters.

Another object of the invention is to 40 provide a steam heater for air or other gas in combination with the vulcanizer whereby moisture of the steam cannot mix with the air and affect the articles to be treated by the air.

45 The foregoing and other objects will become apparent as the following description is read in connection with the accompanying drawings, it being understood that the invention is not limited to the specific forms 50 thereof described below and illustrated in the drawings.

Of the accompanying drawings:

Figure 1 is a side elevation partly in section of a vulcanizer embodying the invention;

Figure 2 is a top plan view thereof;

Figure 3 is an enlarged end elevation thereof;

Figure 4 is an enlarged transverse section on line 4—4 of Figure 1;

Figure 5 is an enlarged transverse section on line 5—5 of Figure 1; and

Figure 6 is a transverse section similar to that shown in Figure 4 but illustrating the invention as employed in a form of heater 65 now generally employed.

Referring to the drawings, 10 represents a horizontal vulcanizer composed of a plurality of cylindrical sections 11, 11 which may be butt jointed as at 12, the joints 12 being sealed by rings indicated at 13. The vulcanizer is sealed at one end by a section 14 and at the other end 15 by a suitable door (not shown).

As is usual in horizontal vulcanizer constructions, a track including rails 16, 16 is arranged in the bottom portion of the vulcanizer 10, but in this particular construction the rails 16 are supported by brackets 17, 17 adapted to space the rails out of engagement with the wall of the vulcanizer so that there will be a substantial space beneath them as indicated at 18, 18.

For circulating a heated gas such as air through the vulcanizer 10, a suitable fan or blower 19 is employed, the discharging side of the blower 19 being connected to a header 20 from which extends a number of branches 21, 21 for conducting the air or gas to spaced points in the top of heater 10. Branches 21 are connected to suitable fittings 22 secured on the vulcanizer 10 over inlet openings 23 (Figure 4) through which the air or other gases are conducted into the vulcanizer.

Arranged in the vulcanizer 10 is a baffle 24 for carrying the entering air or gases about the vulcanizer close to the outer walls on both sides thereof so that a layer of heated air or gas will insulate the interior of the vulcanizer from the outer atmosphere. The baffle 24 preferably extends about the wall of the vulcanizer in close relation thereto down to the rails 16, under which the air will pass from behind the baffle into the chamber proper of the vulcanizer. Since the air will be directed in opposed currents between the rails, it will tend to uniformly mix as indicated by the arrows in Figures 4 and 5 and will rise in the vulcanizer.

At the top of the vulcanizer 10 between

2
the inlets 23 there are arranged a suitable number of outlets 25 (Figure 5) which are formed by fittings 26 for conducting the air through the baffle space and through outlets 27 in the vulcanizer into fittings 28 which are connected by branches 29 to a header 30.

The header 30 is connected to a heater indicated in general by the numeral 31 and 10 formed of a heater header 31^a connected to a series of pipes 32, 32 through which the vulcanizing medium is conducted, the pipes 32 being non-jointed and surrounded by pipes 33, 33 through which a heating medium, such 15 as steam may be circulated in any suitable manner. The pipes 32 are connected to a second heater header 31^b which is connected to the entering side of fan or blower 19.

In the form of the invention shown in Figure 6, the baffle 24 is mounted in a steam shell 20 vulcanizer 35 chambered as at 36 for the reception of steam. The air may be circulated through this vulcanizer by similar apparatus to that described above with the exception that heater 31 will not be used. In 25 this form the layer of entering air will rapidly absorb heat from the steam chamber 36 and will insulate the chamber from local action of the steam jacket on rubber articles 30 supported adjacent the walls of the vulcanizer.

In practising the preferred method with either form of apparatus, the articles usually on mandrels or lasts are supported on a suitable truck (not shown) which is run into the vulcanizer onto tracks 16, the end 15 of the vulcanizer being then sealed. Air or other gas is circulated through the vulcanizer, the air being heated to the desired temperature 35 of cure and preferably being at higher than atmospheric pressures at the start of the process to compact the articles onto the mandrels and prevent blistering. The air is divided into two currents by baffle 24, the 40 currents being carried around the wall of the vulcanizer on opposite side thereof until they are directed from beneath the rails 16 against each other whereupon they thoroughly mix and assume a uniform temperature 45 and pass upwardly about the articles to be vulcanized.

After an initial curing period at higher pressures and before the combined heat and 50 pressure of the air can deteriorate the rubber or the coatings ordinarily applied to boot and shoe goods, the pressure of the circulating air is reduced to substantially atmospheric at which pressure the air is kept until the vulcanization is complete.

It will be seen that the baffle 24 serves to 55 provide intimate mixture of the circulating gases in the heater, it also forms a layer of rapidly changing air about the vulcanizer which will protect articles close to its walls from either "under cure" in the case of the

vulcanizer 10 or "over cure" in the case of the vulcanizer 36, and also all the articles from the direct action of the spaced entering currents of air. With the use of the baffle 24 in the vulcanizer 36 there is the 70 additional advantage that the air is traveling at considerable velocity over the inner surfaces of chamber 36 and thus rapidly and effectively comes up to the desired curing temperature. 75

Heating of the air in heater 31 is preferred for the reason that by the arrangement shown, there being no joints in pipes 32, there will be tendency for steam to leak into the circulating air and thus ruin such article. 80 as boots and shoes not yet cured and the coatings of which in the uncured state are likely to be deteriorated by moisture.

Modifications of the invention other than those disclosed herein may be resorted to 85 without departing from the spirit thereof or the scope of the appended claims. For example, some of the benefits of the invention could be obtained by passing the air or gas first over the articles and then about the 90 walls of the vulcanizer.

What is claimed is:

1. Heating and vulcanizing apparatus comprising a chamber, means for circulating a heated fluid through the chamber, and 5 means for causing the fluid to take a plurality of paths downwardly about the chamber close to its walls, to then direct the plurality of currents against each other in the bottom of the chamber to thoroughly mix the 100 same and finally to permit the mixed currents to pass upwardly over the articles to be treated.

2. A vulcanizing apparatus comprising a chamber, an inlet adjacent the top of the 105 chamber and a baffle in the chamber beneath the inlet and extending about the chamber in close relation to the walls thereof and terminating at points on each side of the chamber closely adjacent the bottom of the 110 chamber.

3. A horizontal vulcanizer comprising a chamber, an inlet adjacent the top of the chamber, and a baffle in the chamber beneath the inlet to direct fluids entering the 115 inlets in paths downwardly about both sides of the chamber adjacent its wall.

4. A horizontal vulcanizer comprising a chamber, an inlet adjacent the top of the chamber, and a baffle in the chamber beneath the inlet, said baffle extending in close 120 relation to the walls of the chamber on both sides thereof and terminating closely adjacent the bottom thereof to direct fluid admitted through the inlet into opposed streams at the bottom of the vulcanizer.

5. A horizontal vulcanizer comprising a chamber, a track in the bottom of the chamber, the rails of said track being spaced from the bottom of the chamber, an inlet adjacent 125

- the top of the chamber and a baffle beneath the inlet and formed so as to extend in close relation to the wall of the chamber from one rail to the other of the track.
6. A vulcanizing apparatus including a vulcanizer, means for circulating air or other gases therethrough, and a heater in the circulating system including a series of jacketed pipes, said pipes being jointless whereby leakage of steam into the system is prevented.
7. A vulcanizing apparatus including a vulcanizer, means for circulating air or other gases therethrough, and a heater in the circulating system including a series of steam jacketed pipes, said pipes being jointless whereby leakage of steam into the system is prevented.

BOY W. BROWN.
